UNITED STATES PATENT OFFICE.

CHARLES H. ROTH, OF CHICAGO, ILLINOIS.

DESIGN FOR A DYNAMO-CASING.

SPECIFICATION forming part of Design No. 34,452, dated April 30, 1901.

Application filed March 22, 1901. Serial No. 52,440. Term of patent 7 years.

To all whom it may concern:

Be it known that I, CHARLES H. ROTH, a citizen of the United States, and a resident of Chicago, in the county of Cook and State of Illinois, have invented and produced a new and original Design for Dynamo-Casings, of which the following is a specification, reference being had to the accompanying drawings, forming a part thereof.

10 In the accompanying drawings, Figure 1 is an end elevation of a dynamo-casing made according to my new design, and Fig. 2 is a side elevation of the same.

The leading or material feature of my design is the dynamo or motor casing consisting of the spheroidal shell having a widened base and having its axis parallel with said base, having circular openings at its poles, each surrounded by a split boss, said bosses and 20 base being integral with said shell.

The globular shell 1 has at each end of its

horizontal diameter a boss 2, having a circular opening 3 in its center. At each side of these bosses a portion of the shell is cut away, leaving the openings 4 through said shell. 25 Below the shell and integral with the same is the base 5, having the gussets 6, joining the lower part of the shell on each side. Each of the bosses 2 is cut into two parts by the slit 7 and is extended at said slits to form the 30 flanges 8.

What I claim as new, and desire to secure by Letters Patent, is—

The design for a dynamo-casing, substantially as herein shown and described. 35

Signed by me at Chicago, Illinois, this 20th day of March, 1901.

CHARLES H. ROTH.
